Attorney

UNITED STATES PATENT OFFICE.

WILLIAM A. LEE, OF ROSELAWN, INDIANA.

CIRCUIT-CLOSING DEVICE.

Application filed June 19, 1923. Serial No. 643,408.

To all whom it may concern:

Be it known that I, WILLIAM A. LEE, a citizen of the United States, residing at Roselawn, in the county of Newton and 5 State of Indiana, have invented certain new and useful Improvements in Circuit-Closing Devices, of which the following is a specification.

My invention relates to a device for stopping the operation of the internal combustion engines of vehicles, such as tractors, automobiles, aeroplanes or the like, when the vehicle assumes an angular position, beyond a predetermined limit.

10 An important object of the invention is to provide a device of the above mentioned character, which is universal in operation, stopping the operation of the engine when tilting to or beyond a selected angle, in any

20 direction.

A further object of the invention is to provide a device of the above mentioned character, which is simple in construction, reliable in operation, and may be easily installed upon the engine and associated with the ignition circuit thereof.

25 A further object of the invention is to provide a device of the above mentioned character, which is particularly well adapted for use in connection with the engines of tractors, to prevent the same from tilting rearwardly, which frequently occurs when the load is excessive or an obstruction encountered so that the load cannot be drawn 30 by the tractor.

Other objects and advantages of the invention will be apparent during the course of the following description.

35 In the accompanying drawings, forming a part of this specification, and in which like numerals are employed to designate like parts throughout the same,

40 Figure 1 is a side elevation of a device embodying my invention, showing the same in use,

Figure 2 is a central vertical sectional view through the device, and,

45 Figure 3 is a plan view of the same.

In the drawings, wherein for the purpose 50 of illustration is shown a preferred embodiment of my invention, the numeral 5 designates an internal combustion engine, and 6 a source of current included in the ignition circuit. This source of current 6 may be a 55 battery or the secondary coil or coils included in the usual ignition system. A wire

7 is connected with one pole of the source of current and grounded, and a wire 8 is connected with the opposite pole of this source of current and leads to the spark plugs. The 60 numeral 9 designates the ground connection of the engine.

My circuit closing device embodies a tapered or conical shell casing 10, decreasing in diameter downwardly, with its lower 65 end closed for receiving or holding movable circuit closing means, illustrated in the form of a plurality of metal balls 11. Instead of employing these balls, I may employ any form of rolling contact element or elements 70 and also contemplate using mercury. The shell 10 is formed of metal, and is supported by a pair of vertical legs 12, also formed of metal, and in electrical connection therewith. These legs have apertured feet 13, for 75 receiving certain of the bolts 14, which serve to hold the head of the engine block in place. The shell 10 is therefore in electrical connection with the engine. The numeral 15 designates a top or cover for the shell 10, 80 which is also formed of metal. This cover is thoroughly insulated from the shell 10 by means of an insulating gasket or ring 16. The cover 15 is secured to the upper end of the shell 10 by bolts 17 or the like, which 85 are thoroughly insulated from the cover 15.

Arranged within the conical shell 10 is a tapered or conical obstruction element 18, which decreases in diameter downwardly, as shown. This obstruction element is preferably formed of insulating material such as 90 porcelain, wood or the like. This obstruction element is provided upon its periphery with spaced annular obstruction elements or ribs 19, integral therewith. These ribs are 95 annular and are spaced from each other in vertical relation and are also spaced from the shell 10, as shown. The obstruction element 18 is attached to the cover 15 by means of a rod or bolt 20, engaging this cover, and thoroughly insulated therefrom, as shown.

Secured to the cover 15 is a binding post 21, having connection with a wire 22, connected with the wire 8 of the ignition circuit.

105 With the circuit closing device arranged as shown in Figure 1, it is obvious that should the engine 5 tilt in any direction, beyond a predetermined limit, the ball or balls 11 will roll down the shell 10 and form an 110 electrical connection between the shell and the cover 15. A short circuit will thereby

be closed and the current will flow from the source of current 6 through wire 8, wire 22, cover 15, balls 11, shell 10, leg 12, engine 5, ground 9, and ground 7 back to the opposite pole of the source of current 6. It is thus apparent that the short circuit will be closed when the engine tilts in any direction. An important feature of the invention is the provision of the obstructing elements or ribs 19, which function to check or prevent the upward movement of the balls, due to the sudden jars or vibrations transmitted to the engine, whereby the short circuit will not be improperly closed. These obstruction elements do not interfere with the closing of the short circuit when the engine tilts, as explained. When the device is tilted, the balls 11 run down the side of the shell 10, and do not contact with the obstruction elements or ribs 19, and hence these ribs do not function. When the balls are thrown suddenly upwardly, by jars or the like, they strike against certain of the ribs 19, depending upon their particular direction of movement, and hence are returned to the bottom of the shell, without contacting with the plate 15.

The invention is of course in no sense restricted to the precise location of the circuit closing device, as indicated in Figure 1. The device may be located upon any suitable part of the engine, or frame of the automobile. The device is also adapted for use in connection with any form of vehicle, such as tractors, automobiles, or aeroplanes. In the event that the vehicle should turn over, as occurs frequently with automobile wrecks, it is obvious that the engine will be stopped, thereby preventing fires, which frequently occur under these circumstances. The same will be true in the event that the device was used upon aeroplanes.

It is to be understood that the form of my invention herewith shown and described is 45 to be taken as a preferred example of the

same, and that various changes in the shape, size, and arrangement of parts may be resorted to without departing from the spirit of my invention, or the scope of the subjoined claims.

Having thus described my invention, what I claim is:

1. A device for use in connection with an internal combustion engine for short circuiting the ignition circuit of the same when the engine inclines beyond a predetermined limit, comprising an upstanding tapered metal shell decreasing in diameter downwardly, a metal cover for the shell insulated therefrom, a tapered obstructing member arranged within the shell and decreasing in diameter downwardly and spaced from said shell, said member having vertically spaced obstructing elements formed thereon, movable circuit closing means mounted within the shell and adapted to electrically connect said shell and cover, a binding post secured to the cover, and an electrical connection secured to the shell.

2. A device for use in connection with an internal combustion engine for short circuiting the ignition circuit of the same when the engine inclines beyond a predetermined limit, comprising an upstanding tapered metal shell decreasing in diameter downwardly, a contact element arranged at the upper large end of the shell and insulated therefrom; a tapered obstruction member mounted within the shell and decreasing in diameter downwardly and provided with obstruction elements, movable circuit closing means mounted within the shell and adapted to electrically connect said shell and contact element, an electrical connection secured to the contact element, and an electrical connection secured to the shell.

In testimony whereof I affix my signature.

WILLIAM A. LEE.
